BUILDING BLOCK FOR APERTURED WALL

George B. Muse, Hillcrest Drive,
Calhoun, Ga. 30701

Continuation of design applications Ser. No. 6,167,
Mar. 10, 1967, and Ser. No. 7,427, June 12, 1967.

This application Feb. 19, 1968, Ser. No. 13,008

Term of patent 14 years

Int. Cl. D25—01

U.S. Cl. D18—2

FIG. 1 is a perspective view of an end surface and the top surface of the building block for apertured wall;

FIG. 2 is a perspective view of the end surface opposite from that shown in FIG. 1 and the bottom surface of the building block;

FIG. 3 is a top plan view of the building block;

FIG. 4 is a side elevational view, in cross section, of the building block;

FIG. 5 is a bottom plan view of the building block;

FIG. 6 is a side elevational view of the building block;

FIG. 7 is an end elevational view of the building block;

FIG. 8 is a perspective view of an end surface and the top surface of a modified form of the building block;

FIG. 9 is a perspective view of the end surface opposite from that shown in FIG. 8 and the bottom surface of the modified building block;

FIG. 10 is a top plan view of the modified building block;

FIG. 11 is a side elevational view, in cross section, of the modified building block;

FIG. 12 is a bottom plan view of the modified building block;

FIG. 13 is a side elevational view of the modified building block;

FIG. 14 is an end elevational view of the modified building block.

This application is a continuation of application Ser. No. 6,167, filed Mar. 10, 1967, and of application Ser. No. 7,427, filed June 12, 1967, both now abandoned.

I claim:

The ornamental design for a building block for apertured wall, as shown and described.
